H. N. OTT,
ELECTRODE HOLDER FOR ELECTRIC ARC LAMPS.
APPLICATION FILED SEPT. 15, 1915.

UNITED STATES PATENT OFFICE.

HARVEY N. OTT, OF BUFFALO, NEW YORK, ASSIGNOR TO SPENCER LENS COMPANY, OF BUFFALO, NEW YORK.

ELECTRODE-HOLDER FOR ELECTRIC-ARC LAMPS.

1,273,915.

Specification of Letters Patent.

Patented July 30, 1918.

Application filed September 15, 1915. Serial No. 50,892.

To all whom it may concern:

Be it known that I, HARVEY N. OTT, a citizen of the United States, residing at Buffalo, in the county of Erie and State of New York, have invented a new and useful Improvement in Electrode-Holders for Electric-Arc Lamps, of which the following is a specification.

This invention relates to holders for the carbons or electrodes of electric arc lamps and the object of the invention is to provide a practical and desirable electrode holder of simple and inexpensive construction, which will securely hold the carbon or electrode and which can be readily adapted for holding carbons or electrodes which differ considerably in size.

In the accompanying drawings:

Figure 1 is a side elevation of the electrode supporting and adjusting means of an electric arc lamp provided with holders embodying the invention.

Fig. 2 is a sectional elevation thereof, on an enlarged scale, in line 2—2, Fig. 1, showing one of the electrode holders.

Figs. 3 and 4 are similar views showing the holder adjusted for carbons of different sizes.

Fig. 5 is a detached perspective view of one of the jaws or members of the holder.

Fig. 6 is a detached perspective view of the other jaw or member of the holder.

Fig. 7 is a bottom plan view of the lower end portion of the holder.

A and B represent the two carbons or electrodes of an electric arc lamp and C and D represent holders in which the carbons or electrodes A and B are respectively secured and by which they are adapted to be fed or adjusted toward each other.

The holders are substantially alike in construction and the following description of the holder C applies also to the other holder D.

The holder comprises a relatively stationary jaw or member 1 and a movable jaw or member 2 which is fulcrumed on the stationary jaw and is adapted to be moved toward the same by a thumb screw 3 for clamping the carbon or electrode between the two jaws and rigidly securing it in the holder. The stationary jaw 1 is preferably provided with a transverse V-shaped notch or seat 4, in which the carbon rests and is

held by the movable jaw 2, and is provided at one side of the electrode seat 4 with a projecting fulcrum post or part 5 with which the movable jaw 2 has a detachable fulcrum engagement. Preferably, the fulcrum post 5 is provided with fulcrum pins 6 and 7 which project laterally to opposite sides thereof, and the movable jaw 2 is slotted or bifurcated at one end, as indicated at 8 in Fig. 6, to straddle the post 5 beneath one or the other pair of pins 6 or 7. The movable jaw 2 is provided at its opposite end or at the portion thereof at the opposite side of the electrode seat from the fulcrum post with a hole 9 through which the thumb screw 3 loosely passes, the thumb screw entering and being adapted to turn in a screwthreaded hole in the stationary jaw or member 1. The head of the thumb screw engages the outer side of the movable jaw so that the movable jaw is forced toward the stationary jaw by screwing up the thumb screw. Between its ends, opposite the seat in the stationary jaw, the opposite sides of the movable jaw are of different formation, one side 10 being, for instance, substantially flat or straight, while the opposite side has a raised portion 11 and the movable jaw is adapted to be placed with either its straight face 10 or the raised portion 11 facing and adapted to bear on the carbon or electrode. If the movable jaw is placed as indicated in Fig. 2, with its straight side 10 against the carbon or electrode and with its bifurcated end under the lower pair of fulcrum pins 6, it is adapted to grip and firmly hold a carbon or electrode A of a size such as indicated in Fig. 2. By removing the movable jaw and reversing it so as to place its raised portion 11 against the carbon and with its bifurcated end beneath the same pair of fulcrum pins, the holder is adapted to hold a smaller carbon A', as indicated in Fig. 4. By placing the movable jaw with its bifurcated end beneath the upper pair of fulcrum pins 7 and with its raised portion 11 against the carbon, the holder will properly grip and hold a carbon of larger size than when the movable jaw is placed as shown in either Fig. 2 or Fig. 4, and the holder can be adapted for a still larger sized carbon by reversing the movable jaw so that its straight side will bear upon the carbon while its bifurcated end engages the upper

pair of fulcrum pins 7. Thus by placing the movable jaw in one or the other of its reversible positions and engaging it with one or the other pair of fulcrum pins, the holder 5 is adapted for holding carbons of four different sizes. In all of its several different positions, the movable jaw occupies such an angular relation to the stationary jaw that the holder is equally efficient in the several 10 different adjustments of the movable jaw and can be readily operated by turning the thumb screw to firmly grip and hold the carbon. To change the movable jaw from any one to another of its several different 15 operative positions it is only necessary to unscrew the thumb screw and slip the movable jaw out of engagement with the fulcrum post, again place it in connection therewith in the desired position, and replace the 20 thumb screw.

Manifestly the holder can be adapted for a greater or less number of different sizes of carbons by employing the requisite number of fulcrum pins on the post 5.

25 In the construction shown, the holders C and D are secured respectively to slides or carriages 12 and 13 which are adjustable lengthwise of the carbons or electrodes in the supporting frame or structure of the 30 lamp. As shown, the stationary jaw of each holder is provided with a shank 14 which is secured by a clamping plate 15 and screws 16 to the slide or carriage, the holder being suitably insulated from the slide or carriage. 35 The slide or carriage 12 is slidably mounted on a guide rod 17 secured to the supporting frame 18, and is provided with shoulders or portions 19 adapted to engage the edges of the frame 18 for holding the 40 slide from turning on the guide rod. The other carriage 13 is similarly mounted and guided on the frame 18. The slide or carriage 12 is adjusted along its guide rod by a hollow screw shaft 20 which is journaled 45 in the frame 18 and is provided with a screw thread engaging a threaded arm or lug 21 on the slide or carriage 12. This adjusting shaft is adapted to be turned by a thumb wheel or knob 22 at its end. The slide or 50 carriage 13 for the other carbon is adjusted by a shaft 23 having a screwthread engaging a lug on the carriage or slide, and this shaft is connected by bevel gears 24, 25 to an operating shaft 26 which extends through 55 the hollow shaft 20 and is provided at its

outer end with a knob or wheel 27 for turning it.

The manner of mounting and adjusting the carbon holders above described is not a part of the invention and is not claimed 60 herein. The holders could be adjustably mounted and adjusted in any other suitable manner.

I claim as my invention:

1. In an electrode holder adapted to hold 65 electrodes of different sizes, the combination of a stationary jaw and a movable jaw between which the electrode is held, said stationary jaw having a post provided with fulcrum projections at different distances 70 from the body of said jaw, said movable jaw having a slotted end adapted to straddle said post and to engage with one or another of said projections, and means for pressing said movable jaw against an electrode. 75

2. In an electrode holder adapted to hold electrodes of different sizes, the combination of a stationary jaw and a movable jaw between which the electrode is held, said stationary jaw having a plurality of fulcrum 80 projections arranged at different distances from the body of said jaw, said movable jaw having one end which is adapted to be inserted into engagement with one or another of said projections, and a screw extending 85 through the other end of said movable jaw and adapted to move said movable jaw to clamp said electrode.

3. In an electrode holder adapted to hold 90 electrodes of different sizes, the combination of a stationary jaw and a movable jaw between which the electrode is held, said stationary jaw having a plurality of fulcrum projections arranged at different distances 95 from the body of said jaw, said movable jaw having one end which is adapted to be inserted into engagement with one or another of said projections, said movable jaw having sides of different formation and being adapted to be reversed to have either of said sides 100 face said stationary jaw, and means for pressing said movable jaw against said electrode.

Witness my hand, this 10th day of September, 1915.

HARVEY N. OTT.
